LOG CABIN CONSTRUCTION

John G. Baker, Saunderstown, R. I.

Application February 25, 1942, Serial No. 432,345

1 Claim. (Cl. 20—4)

The present invention relates to new and useful improvements in log cabins, and has for its primary object to provide, in a manner as hereininafter set forth, a joint of novel construction for the logs which will be positively weatherproof.

Another very important object of the invention is to provide a log cabin of the character described comprising a novel construction, combination and arrangement of door and window frames, corners, et cetera, whereby the structure will be self-supporting and the use of an inner frame or studding rendered unnecessary.

Other objects of the invention are to provide a log cabin construction of the aforementioned character which will be comparatively simple, strong, durable, attractive in appearance and which may be manufactured and erected at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a door opening in a log cabin constructed in accordance with the present invention.

Figure 2 is a vertical sectional view, taken substantially on the line 2—2 of Figure 1.

Figure 3 is a view in horizontal section, taken substantially on the line 3—3 of Figure 1.

Figure 4 is a view in front elevation of the abutting end portions of a pair of the wall logs.

Figure 5 is a view in end elevation of one of the wall logs.

Figure 6 is a detail view in perspective of the spline which is used between the abutting ends of the wall logs.

Figure 7 is a view in front elevation of a window in the cabin.

Figure 8 is a vertical sectional view, taken substantially on the line 8—8 of Figure 7.

Figure 9 is a view in horizontal section, taken substantially on the line 9—9 of Figure 7.

Figure 10 is a view in horizontal section through an inside corner.

Figure 11 is a view in horizontal section through an outside corner.

Figure 12 is a view in vertical section, showing the rafter framing at one of the walls.

Figure 13 is a top plan view thereof with the boards omitted.

Figure 14 is a view in horizontal section through a modification of the window structure, which

modification may also be used in the door construction.

Figure 15 is a top plan view, showing a modification of the outside corner construction.

Referring now to the drawing in detail, it will be seen that reference numeral 1 designates a concrete foundation. Plates 2 are mounted on the foundation 1. The plates 2 support joists 3. The joists 3 support a floor 4 and a sub-floor 5.

Erected on the plates 2 are horizontal wall logs 6, the lowermost of certain of which the ends of the joists 3 abut, as shown to advantage in Figure 2 of the drawings. The logs 6 are formed to provide top and bottom bearing surfaces 7 and 8, the inner faces 9 of said logs being flat. The outer surfaces of the logs 6 are substantially rounded, as at 10. Rising from the tops 7 of the logs 6 are longitudinal tongues 11, said tongues being on the inner portions of said logs.

The tongues 11 are engageable in grooves 12 which are provided therefor in the subjacent logs. The tops and bottoms of the logs 6 are further provided with opposed, complementary substantially V-shaped grooves 13 defining a passage for the reception of a suitable sealing medium. The bottoms 8 of the logs 6 are still further provided, on their outer portions, with depending lips or aprons 14 which are engageable in rabbets 15 which are provided therefor in the tops of the subjacent logs. The rabbets 15 are inclined outwardly slightly to better shed water.

The ends of the wall logs 6 which abut have formed therein opposed saw cuts or kerfs 16. The kerfs 16 extend diagonally between the tops and bottoms of the logs 6 from the inner sides of the tongues 11 to the inner portions of the lips or aprons 14. The kerfs 16 are for the reception of metallic splines 17 which render the joint substantially air and water-tight even though the logs should shrink.

In Figures 1, 2 and 3 of the drawings, a door frame is designated generally by reference numeral 18. The frame 18 includes vertical side members 19 of substantially the cross-sectional shape shown in Figure 3 of the drawings. Extending between the lower end portions of the side members 19 is a threshold 20. A header 21 extends between the upper end portions of the side members 19. The joint between the threshold 20 and the subjacent log 6 is substantially the same as the joints between said logs. This is also true of the plates 2 and the logs 6 resting thereon. Facing strips 22 are provided on the

inner faces of the members 19 and 21 of the door frame 18.

Mounted above the header 21 is a cap log or member 23. The outer portion of the header 21 has formed therein a rabbet 24. The rabbet 24 accommodates an apron 25 which depends from the outer portion of the cap log 23, thus providing a water-tight joint without the necessity of using flashing. The header 21, it will be observed, is spaced below the cap log 23 and the apron 25 for permitting the walls to settle. This is indicated at 26 in Figure 2 of the drawings.

In Figures 7, 8 and 9 of the drawings, a window frame is designated generally by reference numeral 27, said frame having mounted therein a casement sash 28. The window frame 27 includes an outwardly protruding sill 29. Mounted on the inner portion of the sill 29 and projecting inwardly therefrom is a stool 30. Depending from the inner edge of the sill 29, beneath the stool 30, is an apron 31. In other respects, the window frame 27 is substantially similar in construction to the door frame 18. As seen in Figures 3 and 9 of the drawings, the vertical side members of both the door and window frames 18 and 27, respectively, have formed in the inner portions of their outer sides rabbets 32 for the reception of tenons or the like 33 on the adjacent ends of the logs 6.

In Figure 10 of the drawings, an inside corner structure is designated generally by reference numeral 34. In this inside corner, one of the logs 35 has formed in one end portion a comparatively long stepped rabbet 36. The adjacent end of the other log 37 abuts the longitudinal wall of the rabbet 36 and has formed therein a complementary but comparatively short rabbet 38. The rabbets 36 and 38 accommodate a vertical corner post 39.

In Figure 11 of the drawings, an outside corner is indicated at 40. In this construction the right angularly extending logs alternately cross and project beyond each other. The inner sides of the comparatively long logs, as at 41, have formed therein vertical grooves or channels 42 for the reception of tongues or tenons 43 which project from the opposed, abutting ends of the comparatively short logs, as at 44. The end portions of the tongues 43 are removed to permit the crossed logs to rest flat on the subjacent logs. An inside corner piece is indicated at 45.

Referring now to Figures 12 and 13 of the drawings, what may be referred to as a wall rafter log is indicated at 46. A log rafter resting on the member 46 is indicated at 47. At the points where they intersect, the members 46 and 47 are notched or recessed and interlocked, as at 48. The upper portions of the rafter logs 47 are preferably flattened to facilitate mounting and securing thereon the roof boards 49.

In the modification of the door frame structure illustrated in Figure 14 of the drawings, the outer sides of the vertical side members 50 and the adjacent sides of the tongues or tenons 51 of the wall logs 6 have formed therein saw cuts or kerfs for the reception of metallic strips 52 of angular cross-section. This modification may also be used in the construction of the window frames.

In the modification of the outside corner construction shown in Figure 15 of the drawings, the inner sides of the comparatively long logs and the abutting ends of the short logs have formed therein opposed, diagonally extending saw cuts or kerfs for the reception of metallic splines 53. Thus, in this embodiment the grooves 42 and the tongues 43 shown in Figure 11 of the drawings are omitted.

It is believed that the many advantages of a log cabin constructed in accordance with the present invention will be readily understood, and although a preferred embodiment is as illustrated and described, it is to be understood that changes in the details of construction and in the combination and arrangement of parts may be resorted to which will fall within the scope of the invention as claimed.

I claim:

A log cabin construction comprising a foundation, plates mounted on said foundation, superimposed wall logs mounted on said plates, and a door frame mounted in the wall logs, said frame including a threshold, vertical side members rising from said threshold, a header extending between the upper portions of the side members, a cap log mounted above the header, and an apron depending from the outer portion of said cap log, the header having a rabbet therein accommodating the apron, said cap log and the apron being spaced from the header.

JOHN G. BAKER.
